Attorney.

UNITED STATES PATENT OFFICE.

WILLIAM H. BRIDGES, OF CINCINNATI, OHIO, ASSIGNOR OF ONE-FOURTH TO MORRIS W. JENNINGS AND ONE-FOURTH TO STANLEY D. HART, BOTH OF CINCINNATI, OHIO.

CIGAR-HOLDER.

1,347,204.

Specification of Letters Patent. Patented July 20, 1920.

Application filed October 23, 1918. Serial No. 259,304.

To all whom it may concern:

Be it known that I, WILLIAM H. BRIDGES, a citizen of the United States of America, and a resident of Cincinnati, in the county of 5 Hamilton and State of Ohio, have invented a new and useful Improvement in Cigar-Holders, of which the following is a specification.

The object of my invention is a cigar holder which will grip a cigar sufficiently 10 to retain it in the holder, but so as to mar the wrapper of the cigar a minimum amount.

This object is attained by the means described in the following specification, and 15 illustrated in the accompanying drawing, in which:

Figure 1, is a side elevation of a cigar holder embodying my invention, the cigar therein being illustrated in the dotted lines.

20 Fig. 2, is a sectional view taken upon line 2-2 of Fig. 1, upon an enlarged scale.

Fig. 3, is a sectional view taken upon line 3-3 of Fig. 2.

Figs. 4, and 5, are views similar to Figs. 25 2 and 3, respectively, but showing the parts in position to hold the cigar in the socket.

Upon the exterior of cigar socket "a⁴" of stock "A," I form longitudinal grooves "a," "a'," and upon the inner wall of socket "a" 30 and near its upper edge I form transverse recesses "a²" "a³," which communicate with grooves "a," "a'."

The grippers comprise longitudinal spring arms "B," "B'," which terminate in transverse arc-shaped fingers "b," "b'." Arms "B," "B'," are seated in the grooves "a," "a'," and are secured at their lower ends to the socket by a stationary band "b²," and at

their upper ends are bent inward and are connected to fingers "b," "b'," which are 40 normally held in recesses "a²," "a³," by the spring arms "B," "B'," upon which a sliding band "D," is mounted, so that in its lower position it leaves the spring arms free, to assume their normal position with the 45 fingers in recesses "a²," "a³," so that a cigar may be inserted readily into the socket and in its outer position presses the spring arms inwardly and causes the fingers to grip the cigar gently so as not to break its wrapper. 50

In Fig. 5, of the drawing the amount the fingers project inwardly is exaggerated for clearness of illustration.

Having thus described my invention, what I claim is:

1. A cigar holder having an internal recess near the outer edge of the socket, a finger normally seated in the recess, a spring arm upon the exterior of the holder projecting inward and engaging the finger, and a 60 means for pressing the spring arm inward to carry the finger out of its recess. 55

2. A cigar holder having internal recesses near the outer edge of the socket, arc shaped fingers normally seated in the recesses, 65 spring arms upon the exterior of the holder at their projection inwardly and engaging the fingers and a sliding band mounted upon the arms and adapted in its inner position to leave the arms free, and in its outer one to 70 press the arms inward to carry the fingers out of the recesses.

In testimony whereof I have hereunto subscribed my name this 21st day of October, 1918.

WILLIAM H. BRIDGES.
